UNITED STATES PATENT OFFICE.

ALBERT NEAL, OF KOKOMO, INDIANA.

LIFTING-JACK.

1,355,843.

Specification of Letters Patent.

Patented Oct. 19, 1920.

Application filed March 29, 1919. Serial No. 286,021.

To all whom it may concern:

Be it known that I, ALBERT NEAL, a citizen of the United States, residing at Kokomo, in the county of Howard and State of Indiana, have invented certain new and useful Improvements in Lifting-Jacks, of which the following is a specification.

This invention relates to that class of lifting-jacks shown and described in my pending application filed October 2, 1918, No. 256,496; and one of the objects of the present invention consists in the provision of a lifting-jack of the above character wherein the construction is considerably simplified, through the elimination of a number of parts, but still enabling the jack to perform all of the work capable of being performed with my former construction.

20 A further object of the invention, in which the number of parts are reduced, enables the present jack to be manufactured more economically, with a corresponding reduction in the cost of replacement of parts, 25 and wherein the liability of the jack becoming impaired is reduced.

I accomplish the above objects of the invention, and such others as may appear from a perusal of the following description 30 and claims, by means of the construction illustrated in the drawings, forming a part hereof, in which—

Figure 1 is a side elevation of my improved lifting-jack, showing the position of the pawls when the actuator-lever is in an elevated position. Fig. 2 is a view similar to Fig. 1, except that the pawls are shown in a changed position, with the actuator-lever depressed. Fig. 3 is a view similar to Fig. 2, except that both pawls are shown as being completely disconnected from the lifting-bar, as when the actuator-lever is in an abnormally depressed condition. Fig. 4 is a view partly in elevation and partly in cross section, on the line 4—4 in Fig. 3. Fig. 5 is a horizontal cross section on the line 5—5 in Fig. 4. Fig. 6 is a view of the opposite side of the actuator-lever from that shown in Fig. 3. Fig. 7 is a view of that side of the jack opposite the side shown in Fig. 3.

50 Referring to the drawings, 10 represents the lifting-jack housing which is provided with a pair of parallel flanges 11 and 12 between which is formed a passageway 13 to provide a guideway for a lifting-bar 14. Flanges 11 and 12 are provided on their op-

posing faces with one or more ribs 15 which engage corresponding channels or grooves 16 in lifting-bar 14 and which prevent the said bar from accidental lateral displacement 60 from passageway 13. Lifting-bar 14 is also provided in one edge with a series of teeth 20 by which bar 14 is engaged and moved longitudinally and held in an elevated position in supporting the load. Lifting-bar 14 is moved 65 longitudinally in passageway 13 by means of a pair of actuator-pawls 22 and 23, the latter terminating at their lower ends in transverse trunnions 24 which engage a pair of apertures 25 properly positioned in the adjacent end of actuator-lever 27 suitably pivoted in extension 28 of lifting-jack housing 10, at 29. By placing apertures 25 at the proper radii from the axis of the pivot 29 they move through a determined arc of 70 travel when lever 27 is oscillated thereby imparting not only the desired throw to pawls 22 and 23 but also imparting an alternating movement to said pawls. As shown in Fig. 1 of the drawings with lever 27 in its elevated 75 position and ready to be depressed, pawl 22 sustains the load while pawl 23 is being lowered from one tooth to the next tooth below, assuming the position shown in Fig. 2 of the drawings. Further depression of 80

lever 27 is prevented by means of a stop-lug 30 on pawl 23 coming into contact with a rotatable stop 31 which is mounted in outer flange 32 of extension 28, of lifting-jack housing 10. On moving lever 27 upwardly, pawl 23 will move lifting-bar 14 upwardly with the load. In fact, pawl 23 performs all the lifting, pawl 22 merely sustaining bar 14 and the load when pawl 23 is disengaged and is moving downwardly over 90 teeth 20 of the bar 14. Examining Fig. 4 of the drawings, it will be noted that stop 31 is formed on a reversed curve and occupies a position so that its upper end will be contacted by stop-lug 30 when lever 27 is depressed, 95 and the lower end of stop 31 is contacted by a-boss 35 (Fig. 2) whereby the upward movement of lever 27 is limited. Stop 31 may be rotated by means of a thumb-nut 36 so as to shift its upper end out of the path of travel 100 of stop-lug 30, thereby permitting lever 27 to be depressed an abnormal distance. This movement is sufficient to carry both the trunnions 24 of pawls 22 and 23 in advance of a perpendicular plane extending through 105 pivot 29 and disconnect both of said pawls from the teeth 20 in lifting-bar 14, thereby

allowing the latter to drop and assume the position shown in Fig. 3 of the drawings.

To prevent displacement of lever 27 from extension 28 of lifting-jack housing 10, I provide the pivot 29 with a head 40 which is inserted through an aperture 41 in side wall of extension 28, which aperture is somewhat above the normal working position of the pivot, the latter being moved into its normal operative position by means of a slot 42 which communicates with aperture 41.

Pawl 22 and 23 are held against accidental displacement by their arrangement between the adjacent inner wall of extension 28 and a flange 45 (Figs. 6 and 7) on lever 27, said flange being formed by cutting away a part of the stock of one side of the inner end of lever 27.

By means of the herein described arrangement of the pawls and their connection relatively to the axis of the pivot 29, on which actuator-lever 27 swings, the necessity of springs and similar tension devices for

holding pawls 22 and 23 normally into contact with lifting-bar 14 is eliminated.

Having thus fully described my said invention, what I desire to secure by Letters Patent, is—

A lifting-jack comprising a tooth lifting-bar, means for supporting said bar parallel with its longitudinal plane of travel, a rocking actuator-lever pivoted a determined lateral distance from said bar, a pair of pawls pivoted to said lever and sufficient distances from its pivot to cause disengagement of both pawls from the bar with the lever depressed below its normal range of travel, a stop-plug carried by one of said pawls, and a stop susceptible of being moved into and out of the path of travel of said stop-plug at the will of the operator.

In witness whereof, I have hereunto set my hand and seal at Indianapolis, Indiana, this 21st day of March, A. D. one thousand nine hundred and nineteen.

ALBERT NEAL. [L. S.]
